DESIGN FOR A BLOWPIPE

Leon M. Farnum, Chicago, Ill., and Clarence K. Teamer, Mount Airy, Pa., assignors to The S. S. White Dental Manufacturing Company, a corporation of Pennsylvania

Application November 19, 1936, Serial No. 66,020

Term of patent 14 years

To all whom it may concern:

Be it known that we, Leon M. Farnum and Clarence K. Teamer, citizens of the United States and residents of Chicago, county of Cook, State of Illinois, and Mount Airy, county of Philadelphia, State of Pennsylvania, respectively, have invented a new, original, and ornamental Design for a Blowpipe, of which the following is a specification, reference being had to the accompanying drawing, forming part thereof.

The figure represents a side elevational view of a blowpipe showing our new design, both sides of said blowpipe being alike in appearance.

The characteristic features of our design reside in the handle or body portion which includes a pair of parallel conduits disposed at an angle of substantially 135° with respect to the single conduit leading to the tip of the blowpipe.

We claim:

The ornamental design for a blowpipe as shown and described.

LEON M. FARNUM.
CLARENCE K. TEAMER.
